PROPELLER

Milton D. Thompson, Fairhaven, Mass.

Application August 9, 1937, Serial No. 158,049

7 Claims. (Cl. 170—162)

This invention relates to propellers, particularly that type commonly known as the "feathering" blade. In this type the blades are capable of limited rotation on their own axes.

5 In my present invention I have in view two principal objects,—

First: To provide means whereby that face of the blade which is most efficient for propelling purposes is always used,—either for going ahead 10 or going astern movements of the vessel.

Second: To evolve a propeller in which the blades themselves are utilized in the operation of re-arranging them when a change in the direction of movement of the ship is desired. I accomplish the first object by means which permit the blades to rotate on their axes through an arc of substantially one hundred and eighty degrees, or half a turn.

The second object is attained through the 20 agency of the particular form or contour of the blade, there being an excess of water-impacting surface on one side of the axial line of the blade, making it out of balance, axially.

The preponderance of working face is on the 25 water-leaving or trailing portion of the blade, this portion extending transversely a greater distance from its axial line than does the entering or cutting edge on the opposite side of the axis line. Its action is somewhat analogous to a 30 weather vane, the tail of which swings the vane when the wind shifts from one quarter to another.

When my propeller is employed on auxiliary powered vessels these trailing portions of the blades cause them to automatically come into 35 longitudinal feathering positions when the power is shut off. Immediately the propeller shaft starts to revolve, these trailing portions, by impact on the water, force the blades to turn on their axes a certain amount, the propeller hub mechanism 40 cooperating to bring the blades into their full working pitch positions.

For a clearer understanding of the import of my invention reference should be had to the description found in the following specification 45 when taken in connection with the accompanying drawing in which like reference characters are employed to identify like parts in all the different views thereof. In the drawing,—

Fig. 1 is a side view of the propeller, showing 50 the blades in the "go ahead" positions;

Fig. 2 is the same, except that the blades are positioned to drive the ship "astern";

Fig. 3 shows the blades in "feathering" positions, when the propeller shaft is idle;

55 Fig. 4 shows a fragmentary view of the propel-

ler with one half of the two-part casing removed, the blades being disposed in the "ahead" position;

Fig. 5 is like Fig. 4 except that the propeller-shaft hub has been rotated, relative to the casing, to bring the blades into "astern" positions; 5

Figs. 6 and 7, are respectively, the two grooves in the hub member developed on a plane surface to show their exact contours;

Fig. 8 is a transverse section through the parts, 10 taken on a central line through the blade flanges;

Fig. 9 is a section on line 9—9, Fig. 4, and

Fig. 10 is an end view, partly in section, of one of the propeller blades.

Referring to the drawing, 1 is a propeller shaft, 15 fixedly secured to which, by a key 1a, is a propeller-shaft hub having outer end straight portions 2 and an intermediate part 2a conforming to the shape of a frustum of a sphere.

In the portion 2a are two grooves 3 and 4, one 20 diametrically opposite the other. Both grooves are spiralling and groove 3 somewhat irregular in contour. Should there be more than two blades in the propeller assembly a corresponding number of grooves would be supplied. 25

In Figs. 6 and 7 the contour of these grooves are shown as they would appear were their outlines transferred to a plane surface. Their functions will hereinafter be explained.

Enclosing the propeller-shaft hub is a two-part 30 casing 5, the portions 2, 2 of the hub being journaled in the bearings 6, 6, respectively, of the casing and capable of restricted rotation therein. The outside surfaces of these bearings are screw threaded, at 7, to receive, respectively, the collars 35 8, 8 which serve to rigidly clamp the two similar halves of the casing together.

On opposite sides of the assembled casing 5 are circular flanges 9, the latter being disposed in the circular grooves 10 in the hubs 11 of the propeller 40 blades 12 and 12a, respectively. The hubs 11 of the blades rotate on their axes within the circular flange, but like the propeller-shaft hub, the extent of their rotation is limited.

The faces of the flanges 9 converge slightly to- 45 ward the aft end of the propeller, thus producing an aftward rake to the blades.

On the hub 11 of each blade is a pintle or gudgeon, the pintle 13 on the blade 12 extending into the groove 3 and the pintle 14 on the blade 50 12a engaging the groove 4.

By observing Fig. 3 it will be noted that the form or contour of the blades is unsymmetrical. This makes them out of axial balance, the portion X extending much further from the axial 55

line S—S of each blade than does the cutting-edge portion C. E.

The trailing portion X on the water-leaving side of the axial line of each blade is also greatly in excess of the portion on the opposite side of the axial line when the propeller is viewed normal to, or at a right angle with, the propeller shaft 1. Thus when brought to their full or working pitch positions, (as shown in Figs. 1 and 2), the path 10 cut in the water by the revolving blades lies largely on the trailing (X) side of their respective pivotal center lines.

With the parts arranged as shown in Figs. 2 and 5, and the shaft revolving in the direction 15 indicated by the arrow A, the ship or boat will be propelled "astern", the nut Z indicating that this is the aft end of the propeller shaft. The pintle 13 will be disposed at the rearward end of the groove 3 and the pintle 14 located in a 20 corresponding part of the groove 4.

The positions, relatively, of the pintles in their respective grooves are more comprehensively shown in Figs. 6 and 7, in which the periphery 2a of the propeller shaft hub is developed into a 25 plane surface and the grooves outlined thereon.

Starting with the pintles 13 and 14 in the grooves in which they respectively operate when driving the ship "astern", their positions as represented in the Figs. 6 and 7 are at 13a and 14a, 30 and rotation of the propeller shaft 1 in the direction indicated by the arrow B will drive the ship in the direction just mentioned,—"ahead".

At this point, with the parts arranged as shown in Figs. 2 and 5, let it be assumed that a change 35 in the direction of movement of the ship to "ahead" is desired, to accomplish which it is necessary to re-position the blades so that they will appear as illustrated in Fig. 1.

Now at the start of the change in direction of 40 rotation of the propeller shaft from what is designated as "astern", as indicated by arrow A, to "ahead" which is indicated by the arrow B, the blades lag, or do not immediately and simultaneously respond to the rotary movement of the 45 shaft, and there develops a rotary movement, relatively, between the propeller shaft hub 2—2a and the casing 5. This brings the pintles 13 and 14 from positions 13a and 14a to positions 13b and 14b, respectively.

50 Thus far there will be no appreciable axial rotation of the blade 12a, but, due to the slight lead or advance in this portion of the groove 3, represented by D, the pintle 13 will act to give the blade 12 a comparatively small axial rotation.

55 Now from this point onward (from positions 13b and 14b) the blades have two agencies acting to turn them on their axes, the pintles and grooves being one, and the resistance of the water against which the trailing portions of the 60 blades impact, being the other.

After the pintles 13 and 14 have advanced in the grooves 3 and 4, respectively, to positions 13b and 14b, the pintle 13 engages an abrupt projection 3a extending into the groove 3. This gives 65 the blade 12 a sudden and impulsive axial movement, disaligning temporarily the portions X of the two blades, the pintle 13 moving to position 13c and the pintle 14 at the same time advancing in an easy stage to position 14c, at which positions the two blades are in substantially similar pitch angles with the shaft, and in approximately transverse feathering positions.

As the propeller shaft continues to revolve, the resistance of the water on the blades causes still 70 further movement, relatively, between the hub 75

2—2a and casing 5, and this movement advances the pintles into positions 13d and 14d, the water at this time assisting, in fact acting as the primary agent to continue the axial movement of the blades until they come into positions 13e and 14e, at which places they are disposed at the opposite ends of the grooves 3 and 4 in full working pitch positions for "ahead" movement of the ship. 5

When changing the positions of the blades, 10 from that in which they drive the ship "astern" to that in which they propel it "ahead", the first part of this operation is accomplished mechanically, or through the agency of the pintles and grooves. 15

The reason for this requirement will be apparent when it is borne in mind that during this period (the first portion of the axial turning movement of the blades) the water impacts strongly against the trailing portions X, thereby 20 hindering rather than assisting, by water means, the rotation of the blades on their axes, while the propeller as a whole is revolving.

This condition exists until the blades have 25 axially rotated slightly beyond their transverse feathering positions, at which time the water does assist, in fact almost exclusively provides the means for their axial rotation.

Furthermore, it is obvious that it takes less 30 power, and the parts are subjected to a less amount of strain and wear if, during this mechanically actuated portion of the full axial rotation of the blades, they are acted upon separately. And for this reason and to attain the 35 objects inferred from the foregoing statement, one of the blades is made to rotate on its axis in advance of the other, through the instrumentality of the pintle 13, which is integral with the advancing blade 12, riding the projection 3a, which operation suddenly brings the trailing portion 40 X of the blade 12 out of the circular path of the trailing portion X of blade 12a, and into substantially transverse feathering position where resistance to rotation by and with the 45 propeller shaft is greatly lessened.

After the pintle 13 passes the projection 3a and enters the portion of the groove 3 which is disposed normal to the axis of the propeller shaft, and until it arrived at the position 13c, there is no axial rotation of the blade 12. In other words, 50 after the pintle enters this lead-less portion of the groove 3 the blade 12 ceases to rotate on its axis and is temporarily held in substantially transverse feathering position, in which position there is very little power expended in revolving 55 the propeller insofar as blade 12 is concerned.

Now blade 12a must be brought into the same 60 position, relatively, as that in which blade 12 is at this time disposed,—that is, transverse feathering position.

After the blade 12 ceases to rotate on its axis, the pintle 14, moving along the slot 4, causes the blade 12a to gradually rotate on its axis until upon reaching the location 14c it is disposed in transverse feathering position, comparable to 65 that of blade 12.

The two blades, 12 and 12a, shortly after coming to the positions 13c and 14c, respectively, are brought into their full pitch positions mainly by their impaction on the water, as the propeller 70 as a whole revolves.

A lug 15 on each blade engages a stop member 16 on the casing preventing further axial movement of the blade. A corresponding stop member 75 is provided on the opposite side of the casing.

to limit the axial movements of the blades in the opposite direction.

Fig. 10 shows one of the blades, end on. The full line depiction represents it in longitudinal feathering position, and the dotted line counterpart of the blade illustrates it in full pitch, "ahead" position. Throughout the text of the foregoing specification a so-called "right-hand" screw propeller is contemplated.

10 The arc Y, shown in Figs. 6, 7 and 10, measures the angle through which the blades swing on their axes in moving from positions 13d and 14d to positions 13e and 14e, respectively.

15 The casing 5 may be filled with grease for lubricating the working parts therein, the screw 17 being removed to gain access to its interior.

20 I have hereinbefore described in detail the steps required to be taken to change the positions of the blades from that in which they 25 propel the ship "astern" to that in which the ship is made to move "ahead". The reverse operation, or that in which the blades are positioned in the "ahead" propelling positions and are to be changed to the "astern" ship-driving duty, is 30 conducted and accomplished in a quite similar manner, except for a certain difference in the order or sequence in which the two forces, mechanical and water-impact, are applied to the blades to rotate them on their axes.

35 With conditions such as are presented in Fig. 1, in which is shown a right-hand propeller, rotating as indicated by the arrow B, calculated to drive the ship ahead, and it is desired to re-position the blades to drive the ship astern, the first move is to change the direction of rotation of the shaft, so that it will revolve in the direction of arrow A. Immediately upon reversing the direction of rotation of the shaft the outwardly extending trailing portions X of the blades 40 impact the water and cause the blades to turn on their axes, and this turning movement is continued until the blades arrive at substantially transverse feathering positions and the water no longer has any axially turning effect on the blades. During this portion of their axial-rotating movement the blades have turned in the direction of the arrow M.

45 But as the shaft and blades continue to revolve together, the resistance of the water on the blades is sufficient to cause a movement, relatively, between the casing and the propeller shaft hub, resulting in the pintles and grooves functioning to complete the axial turning movement of the blades and bring them to their full pitch positions to drive the ship astern.

50 So it is evident that the first part of the axial turning movement of the blades is, in this operation, accomplished by water impaction, and the last portion by mechanical means.

55 Now with respect to the change from "astern" to "ahead" movement of the vessel, and the sequence of operations necessary to re-arrange the blades to accomplish this object, we will describe it by starting with the blades arranged as shown in Fig. 2, with the shaft rotating in the direction indicated by the arrow A. The vessel is now moving "astern". But it is desired to arrange the blades so that the vessel will be propelled "ahead". As was the case in the previous 60 change of positions of the blades, the shaft is first made to revolve in the opposite direction, that is, according to arrow B. But in this instance the blades are set so that advantage cannot be taken of the water to start them rotating on their axes, so the first portion of the turning

movement of the blades on their axes must be accomplished through the instrumentality of the pintles and grooves which, by the over-riding action of the casing on the propeller shaft hub, develops a movement, relatively, between these two elements which force the blades into and slightly beyond their transverse feathering positions, at which time the pressure of the water acts on the trailing portions of the blades and quickly brings them into their full pitch positions, for driving the vessel ahead. The blade in this operation turns as indicated by the arrow N, Fig. 5.

10 In contrast with the first operation described wherein the blades were changed from the "ahead" to the "astern" positions, this latter operation where the blades moved from the "astern" to the "ahead" arrangement thereof, started with mechanical actuation of the blades and finished by the impact of the blades on the water.

15 It will be noted that in whichever direction the blades are to be moved for re-positioning, "ahead" to "astern" or vice versa, a greater proportion of the axial movement is brought about through the direct action of the water on the 20 trailing portions of the blades.

25 It is further to be observed that, whether driving the ship "ahead" or "astern", the most efficient and identical working face of the blade does the driving.

30 My propeller has proven very satisfactory in practical use, particularly with respect to its efficiency when the vessel or boat is being driven astern.

35 In auxiliary yacht service the longitudinal feathering feature is of great advantage, as the blades automatically come into positions as shown in Fig. 3 when the shaft stops revolving.

40 Another feature resides in the construction of the blades, which are similar, and one "spare" would fit in place of either of the regular blades should one of them become injured.

45 What I claim is:

1. A propeller mechanism comprising in combination with a propeller shaft, a propeller-shaft hub fixedly secured to said shaft and having two peripheral, spiralling grooves therein extending partially therearound, one of said grooves having, for a predetermined distance from one end, a slight lead, a two-part casing enclosing said propeller-shaft hub, two bearings on opposite ends, respectively, of said casing in which said propeller-shaft hub is journaled and capable of restricted rotation therein, two circular flanges disposed on opposite sides, respectively, of said casing, a propeller blade, having a circumferential groove in its hub portion, rotatively mounted in each of said flanges, and a pintle on the hub of each of the propeller blades, the two pintles adapted to engage, respectively, the two grooves in said propeller-shaft hub.

55 2. A propeller comprising in combination with a propeller shaft, a propeller-shaft hub element fixed on said shaft, the central portion, lengthwise of said hub being frusto-spherical in shape and having a plurality of irregularly contoured grooves in, and advancing along the periphery thereof, a casing, formed of two similar half-portions, having a bearing at each end in which the two end portions of said propeller-shaft hub are 60 respectively journaled, a plurality of propeller blade bearings disposed on the sides of said casing, equally spaced therearound, a propeller blade, having a collared hub portion on its inner end, rotatively mounted in each of said bearings on 65 70 75

- 5 the sides of the casing, a pintle on and extending inwardly from the collared portion of each blade, adapted to engage one of the grooves in the propeller-shaft hub, and cause the blade to which it is attached to rotate on its axis when there is rotational movement, relatively, between said hub and said casing.
- 10 3. A propeller apparatus, adapted to be mounted on the end of a propeller shaft, comprising a propeller-shaft hub, a plurality of outstanding, irregularly contoured walls arranged on the outer surface of said hub, one of said walls lying in a plane substantially at a right angle to the axis of said shaft for a predetermined distance from one end of the wall, and merging into a spiral form as it advances to the opposite end, a two-part casing enclosing said propeller-shaft hub, bearings in the ends of said casing in which the outer end portions of the propeller-shaft hub are mounted for restricted rotation, a collar on each end of said casing securing the two parts together, a propeller blade rotatively mounted on the side of said casing in two or more circumferentially spaced positions thereon, and means interconnecting said propeller blades with the irregularly contoured walls so constructed and arranged that upon rotating said propeller-shaft hub in and with respect to said casing, said propeller blades are made to rotate on their axes.
- 15 4. A propeller apparatus for ship propulsion purposes comprising a plurality of axially unbalanced propeller blades, a pintle on each blade, a two-part casing on the periphery of which a plurality of said blades are mounted for rotation on their axes, a propeller-shaft hub member journaled in said casing and having a plurality of dissimilarly contoured grooves, said grooves being so formed that in changing the direction of rotation of the propeller from driving the ship "astern" to propelling it "ahead", one of said blades starts rotating on its axis in advance of the remaining blades, a lug on each blade, and abutments on said casing, engaged by said lugs to limit axial rotation movements of the blades in each direction.
- 20 5. A propeller adapted to be mounted on the end of a shaft for ship propulsion purposes, comprising a two-part casing, a bearing in each end of said casing, two propeller-blade bearings on opposite sides, respectively, of said casing, an axially unbalanced propeller blade mounted for axial rotation in each of the side bearings in said casing, a pintle on each of said propeller blades, a shaft hub member having two straight end portions journaled, respectively, in the end bearings of said casing and an intermediate por-

tion of spherical zone shape, two grooves, against the walls of which said pintles abut, cut on opposite sides, respectively, of the spherical zone portion of said hub member, one groove starting at the aft end of said portion and continuing therearound for a predetermined distance with slight lead, then spiralling gradually to the forward end of said portion, the other of the said grooves starting at its after end with a slight lead and interrupted by an abrupt projection which causes the engaging pintle to be swung on its orbit quickly to expedite the axial rotation of the blade to which it is attached, and bring this blade into transverse feathering position in advance of the movement of the other pintle which later causes the oppositely disposed blade to be rotated into a relatively similar angular position, both blades from these positions onwardly and until they arrive at their full pitch positions being axially rotated by impaction of their trailing portions on the water.

10 6. A propeller mechanism for ship propulsion comprising in combination with a propeller shaft a propeller-blade-carrying member, means for mounting, for axial rotation, a plurality of propeller blades on said propeller-blade-carrying member, a grooved hub fixed on said shaft, said hub being disposed within, and having restricted rotary movement relative to, said propeller-blade-carrying member, and means associated with said propeller blades, co-acting with said grooved hub member, to rotate said blades on their axes, to the extent that the same cutting edges and driving faces are used in driving the ship either "ahead" or "astern".

15 7. A duplex, reversible-blade propeller comprising in combination with a propeller shaft adapted to revolve in both directions, a shaft hub fixed on said shaft, pintle-engaging means on the periphery of said shaft hub, a two-part casing in which said shaft hub is disposed and its ends journaled, two propeller-blade bearings positioned, respectively, on opposite sides of said casing, the faces of said bearings converging aftward, an axially unbalanced propeller blade, rotatable on its axis and having a hub portion, mounted in each of the propeller-blade bearings, a pintle eccentrically positioned on the hub portion of each blade adapted, in co-action with said pintle-engaging means on the shaft hub, to rotate the blade when movement, relatively, between the shaft hub and the casing occurs, and means to limit the rotary, axial movement of each blade in both directions.

MILTON D. THOMPSON. 55
